PUNCHING MECHANISM FOR PERFORATING
STATISTICAL RECORDS

Daniel Broido, London, England

Application April 28, 1939, Serial No. 270,517
In Great Britain November 18, 1937

4 Claims. (Cl. 164—115)

This invention relates to punching mechanism for perforating statistical records.

The object of the present invention is to provide a group of punching mechanism elements of a compact form adapted to be driven by a group of driven elements on a machine having such elements, possibly the indicating wheels of a device having such indicating wheels, the group of punching mechanism elements being adapted to be initially incorporated into the machine having the driven elements.

Another object of the present invention is to provide a group of punching mechanism elements of compact form and of substantially uniform width adapted to be added later as an attached sub-unit to a machine having a group of driven elements.

One way of carrying out the present invention is illustrated by way of example in the accompanying drawings as applied to a calculating machine which has been fully described and illustrated in my pending U. S. patent application Serial No. 144,022, filed May 21, 1937.

Figures 1 and 1a illustrate together the general arrangement of the machine, these two figures corresponding to Figure 2 of my above mentioned pending patent application.

Figure 2 is a fragmentary section taken on line II—II, Figure 1.

Figure 3 is a side view corresponding to Figure 7 of my above mentioned application, and illustrating the addition of punching mechanism according to the present invention to the machine shown in Figures 1 and 2.

Figure 4 is a section taken on line IV—IV, Figure 3.

Figure 5 is an elevation of the drive side of Figure 4, one gear being partially broken away.

Figure 6 is a section taken on line VI—VI, Figure 3, showing the feed device for the record blank.

Figure 7 illustrates in elevation a punch setting device with a group of punches.

Figure 8 illustrates part of a record produced by the punching mechanism, and

Figure 9 is a side view similar to Figure 3, illustrating a modification.

As above mentioned the construction and operation per se of the calculating machine shown in Figures 1 and 2 has been fully described in my pending patent application Serial No. 144,022, and only a brief description will now be given in order that the operation of the punching mechanism may be understood.

The calculating machine comprises a plurality 55

of result screens 8 and a scanning cylinder 9 fixedly mounted on a shaft 10 adapted to be rotated from the drive of the calculating machine through gearing. The scanning cylinder 9 cooperates with a result screen 8 to control through a photo-electric cell mounted in the interior of the scanning cylinder 9 (and consequently not shown) the setting of eight type-wheels 4, one type-wheel being provided for each column or denomination of the result, said wheels being provided with types or numerals 11. The means for operating the type-wheels comprises a group of eight discs 12, (Figure 2) fixed to rotate with the shaft 10 each disc being formed with a gear element 13. The gear elements 13 are circumferentially displaced relatively to one another and are adapted to drive, respectively, one of a group of eight bushes 14, each of which has a toothed flange 19 adapted to be engaged by a corresponding gear element 13. It will be evident that the bushes 14 are driven successively by the respective gear elements 13. The bushes 14 are loosely mounted side by side on a shaft 20 and are arranged to be coupled by clutches 21 to pinions 22 loosely mounted on the shaft 20. The pinions 22 mesh respectively with pinions 23 (Figures 3 and 1) rigidly connected to the type-wheels 4. Each clutch 21 is separately operated by a clutch fork 24, controlled by an armature 25, all the armatures being commonly controlled by a relay 26 actuated by the photo-electric cell above referred to. The arrangement is such that the pinions 22 are driven for varying periods by the respective clutches 21, the duration 30 of the drive in each case being controlled by the relay 26, in order to bring the eight type-wheels into set positions in which the result of a calculating operation can be printed on a web of paper 27 drawn from supply drum 28. To this end two eccentrics 29 are mounted at each end of the shaft 30 on which the type-wheels 4 are mounted, and these eccentrics are connected to pitmans 31 adapted to reciprocate in guide slots 32 and carrying between them a bracket 33 furnished 45 with a printing pad 39. The arrangement is such that on the termination of a calculating operation the shaft 30 is rotated and the eccentrics 29 cause the printing pad 39 to press the paper 27 against the type-wheels 4 to obtain a printed 50 record of the result of the calculation. As shown in Figure 1 the calculating machine is also provided with accumulator wheels 34 adapted to be driven respectively by gear wheels 35 driven by the gears 23.

The present invention is concerned with punch-

ing mechanism directly coupled to the recording or indicating elements of a calculating machine and arranged to provide a perforated record of the result. In the form shown in Figure 3 of the drawings the punching mechanism is shown as directly coupled to the type-wheels 4 forming the recording elements. The punching mechanism consists of eight groups of punch carriers 41, (Figure 4) one group being operatively associated with each type-wheel 4. Each group of punch carriers comprises ten annular discs 41 held together by rivets 42. Each disc is provided on its periphery with a finger like projection 43 the projections on the various discs being circumferentially displaced so that in general they follow a helical course around the periphery of the group as best seen in Figure 7 which is an elevation of a group of punches. These projections 43 constitute, and will be referred to hereafter as, the punches, and the axial position of each punch in the helix permits it to be identified with one digit value carried on type-wheel with which the group of punches is associated. Each group of discs 41 is mounted tightly on a bush 44 formed at one end with a gearwheel 45, the bushes being loosely mounted side by side on a shaft 46. A direct coupling is provided between each type-wheel 4 and its associated group of punches by means of gearing comprising one of eight gear wheels 47 formed with hubs 48 mounted on shaft 49 and in mesh respectively with the gears 23, a gear wheel 50 mounted on a hub 48 and fixed to the gear 47, two gear sectors 51, 52, the hubs 53, 54 of which are mounted on the shaft 55 and pinned together by pins 56. The gear sector 51 is adapted to be driven by the gear wheel 50 and the gear sector 52 is adapted to drive the gear wheel 45 rigid on a group of punches. The hubs 48 of the gear wheels 47, the hubs 53, 54 of the sectors 51, 52, and the bushes 44 of the groups of punches act respectively as distance pieces to maintain the correct alignment of the elements with which they are associated.

The elements of the punching mechanism and drive thereto above described are mounted between side plates 57, 58 connected respectively to the side plates 59, 60 of the calculating machine by means such as screws 61, and dowel pins 62, the shafts 46, 49, 55 being supported in the side plates 57, 58.

A die-plate 63 provided with a number of transverse die holes 64 equal to the number of punches extends transversely below the punches and is mounted at its ends in horizontal slots 65, 66 in the side plates 58, 57 so as to be movable horizontally within the limits of the said slots.

Means for moving the die-plate 63 in the slots 65, 66 comprises eccentrics 67, 68 fixed to the ends of the shaft 46, these eccentrics being engaged by pitmans 69, 70 carrying the die-plate 63.

A web of paper 71 or other material suitable for the record blank, drawn from reel 72 on shaft 72¹ is passed by two pairs of feed rollers 73, 73 on shaft 76 and 74, 74 on shaft 74¹ (Figures 3 and 6) between the groups of punch carriers 41 and the die-plate 63 and wound up on a draw-off reel 75. The rollers 73, 73 are fixed to a shaft 76 adapted to be driven from the shaft 46 through a unidirectional device comprising a pinion 77 (Figures 3 and 5) splined to the shaft 46, a gear wheel 78 in mesh with the pinion 77, a pawl 79 carried on the side of the pinion 78 and a ratchet wheel 80 fixed to the shaft 76. The shaft 46 is driven through a gear train comprising gear wheels 81, 82, and 83, from the mechanism of

the calculating machine. The gear wheels 81 and 83 are splined to the shafts 30, 46 respectively, the intermediate gear wheel 82 being loosely mounted on a stub shaft 82¹ secured in the side plate 60. The arrangement is such that in one direction of rotation of the pinion 77 the pawl 79 slips over the teeth of the ratchet wheel 80 and does not drive it, whilst in the opposite direction of rotation the pawl 79 engages in the teeth of the ratchet wheel 80 and drives it and the shaft 76. The draw-off reel 75 is driven through a crossed belt 84 passing over a pulley 85 fixed to the shaft 76 and a pulley 86 fixed to the shaft 87 on which the reel 75 is fixedly mounted.

In order to provide for exact registration of the punches 43 in the set positions, with the die-holes 64 in the die-plate 63, eight pawls 88 are provided one behind the other (only one of which is shown in Figure 3) each of which cooperates respectively with the pinion 45 attached to each group of punches, the pawls 88 being mounted on a shaft 89 extending parallel with the shaft 46. Each pawl is pressed by a spring 90 into contact with the teeth of the corresponding pinion 45, the springs having their free ends secured to a bar 91 extending below the punches. When the groups of punches are being driven the pawls 88 slip over the teeth of the pinions 45, but as soon as the drive to the punches ceases the pawls 88 engage immediately in the teeth of the pinions 45 and thus ensure that the punch 43 to be operated of each group registers with a die-hole 64 in the plate 63.

Figure 8 is a fragmentary plan view illustrating a punched record obtained by the punching mechanism described. Each of the undivided rectangles 92 represents an area (which of course is not delineated on the blank record) in which perforations may be made to represent values of one of the eight denominations represented respectively by the eight type-wheels 4. Only three complete areas 92 are shown in Figure 8, but it will be understood that the complete record card will contain eight such areas, one for each denomination. Each rectangular area 92 may be subdivided into ten smaller areas or index points 93, each of which may be perforated to represent any one digit of the denomination represented by the area 92. Thus, the ten index points 93 of each area 92, reading from left to right, may respectively represent the digits 0-9 of each denomination.

It is to be understood that the width of any one rectangular area 92 is equal to the width of one group of punches, and, further, that when the record blank is in position between the groups of punches 41 and the die-plate 63, the areas 92 will be in line respectively with the groups of punches, and the punches 43 of any one group will be in line respectively with the subdivided areas 93, this being effected by reason of the helical arrangement of the punches in the group.

In the record card shown perforations 94 have been made in the three complete areas 92, namely reading from left to right, in the index points 93 marked "5", "3" and "6" of the areas 92. These perforations thus represent digits 5, 3 and 6 of the three denominations represented by these areas. It will be understood that these digits of the three denominations are those which were printed on the web 27 from the types 11 on the type-wheels 4 in respect of a calculation made by the machine, the punches, by reason of being in correct phase or positional relationship with the type-wheels and being directly coupled therewith

so as to be driven thereby, punching the record card in places corresponding to these values.

The operation of the apparatus above described is as follows:

The type-wheels are driven through the respective discs 12, gears 13, toothed bushes 14, clutches 21 and pinions 22, 23, the extent of the drive in each case being controlled by the relay 26 operated by the mechanism of the calculating machine. In this manner the type-wheels are set so that they represent respectively the values of the various denominations of the result of a calculation. The various groups of punch carriers 41 are disposed in correct phase or positional relationship with the associated type-wheels 4 and are driven synchronously therewith through the gearing above described so that when the drive to each type-wheel is disconnected the corresponding group of punches is stopped in a position in which one of the punches 43 carried thereon, corresponding to the value on the type-wheel which will be printed, is brought into operative position relatively to the die-plate 63, the exact registration of the punch with a die-hole 64 in the die-plate being ensured by a pawl 88 as above described.

After one revolution of the shaft 10 all the type-wheels and groups of punches have been set in the required positions in which they remain. The shaft 30 is now driven by the calculating machine drive by means of the gear 81, and the shaft 46 is simultaneously driven through the gear-train 81, 82, 83, and the eccentrics 29, 29, (on the shaft 30) and 67, 68 (on the shaft 46) operate the pitmans 31, 31 and 69, 70. The pitmans 31, 31 cause the printing pad 39 to press the paper 27 on to the type-wheels to receive a printed impression of the result of the calculation, and the pitmans 69, 70 cause the die-plate 63 to approach the punches 43, the record blank being thus perforated by the set punch of each group of punches, as described, and as illustrated in Figure 8. The directions of rotation of the various gears 81—83 during the printing and punching operation are as shown by arrows in Figure 5. It will be seen that when these gears are rotating in the directions indicated, the ratchet wheel 80 is not driven, since the pawl 79 on the pinion 78 merely rides over the teeth of the ratchet wheel. The record blank 71 is thus maintained stationary during the punching operations. When the printing operation has been completed the drive to the gear 81 from the calculating machine is reversed to return the printing pad 39 to the inoperative position. The rotation of the gear 83 is also reversed accordingly, and the die-plate 63 is returned to the inoperative position. During this restoring operation the pawl 79 drives the ratchet wheel 80 and consequently the shaft 76 and rollers 73, 73, the shaft 87 and reel 75 being also driven through the crossed belt 84. The web 71 is thus fed on to the reel 75, presenting a fresh record blank for the succeeding operation.

As illustrated in Figures 3-7, and as above described, the punching mechanism is directly coupled to the type-wheels 4 of a calculating machine. It is evident that the punching mechanism could equally well be directly coupled to other indicating or recording elements of the machine, for example, to direct reading numeral wheels, as shown in Figure 9. This figure is a view corresponding to Figure 3, the main difference being that the printing device comprising printing bracket 33 and pad 39, eccentrics 29,

pitmans 31, the paper web 27 and draw-off rollers therefor, and supply drum 28, all shown in Figure 3, is omitted in Figure 9. Further, the wheels 4 and numerals 11 thereon are made exactly like 5 the wheels 34 (Figure 1) and they are therefore directly readable through a second aperture 40 in the frame of the machine. Thus the punching mechanism is directly coupled to numeral wheels giving a direct reading, instead of to type-wheels adapted to print a record.

In order to avoid unnecessary repetition all such devices which give a direct reading or recording of the result of a calculation are referred to in the appended claims under the generic 15 term "indicating device."

What I claim is:

1. Record-perforating punching mechanism comprising in combination with a plurality of indicating devices, one of said indicating devices being 20 provided for each denomination of the information to be recorded, a plurality of groups of punches, each group being associated with one of said indicating devices and each punch of each group corresponding to one indication on the indicating device with which the group is associated, a die-plate co-operating with the said punches, means for feeding a record blank between said punches and said die-plate, a plurality of punch setting devices each of which is operatively associated with one group of punches and directly 25 coupled to the indicating devices associated with said group of punches so as to be driven by said indicating device, whereby in any operative position of each indicating device the associated punch setting device is in a position relatively to said indicating device in which one punch of the associated group of punches is ready to perforate the record in a place corresponding to the said position of the indicating device, means for providing 30 relative movement between the punches and the die-plate to perform the punching operation, and side plates adapted to be detachably secured to the frame structure adjacent to the indicating devices, all said punches, die-plate, punch setting 35 devices and associated mechanism being carried 40 between said side plates.

2. In record-perforating punching mechanism of the class to be used with a plurality of driven indicating devices, one of said indicating devices 50 being provided for each denomination of the information to be recorded, a plurality of denominational groups of punches, each group being associated with one of the said indicating devices and each punch in each group being associated 55 with one indication on the respective indicating device, a die-plate co-operating with the said punches, means for feeding a record blank between said punches and said die-plate, means for providing relative movement between the said 60 punches and said die-plate to perform the punching of all values of all denominations in one punching operation, a plurality of movable punch carriers constituting punch setting devices, the punches of each denominational group being mounted in fixed positions on an individual punch carrier, each punch carrier being operatively associated with the respective device so that in any operative position of each indicating device, the 65 associated punch carrier is in a position relatively to said indicating device in which one punch of the associated group is set in alignment with the die-plate, to perforate the record in a place corresponding to the said position of the associated indicating device, and means for directly 70 75

coupling each of said punch carriers to its associated indicating device.

3. In record-perforating punching mechanism of the class to be used with a plurality of driven indicating devices, one of said indicating devices being provided for each denomination of the information to be recorded, a plurality of denominational groups of punches, each group being associated with one of the said indicating devices and each punch in each group being associated with one indication on the respective indicating device, a die-plate co-operating with the said punches, means for feeding a record blank between said punches and said die-plate, means for providing relative movement between the said punches and said die-plate to perform the punching of all values of all denominations in one punching operation, a plurality of movable punch carriers, constituting punch setting devices, the punches of each denominational group being mounted in fixed positions on an individual punch carrier, each punch carrier being operatively associated with the respective indicating device, so that in any operative position of each indicating device the associated punch carrier is in a position relatively to said indicating device in which one punch of the associated group is set in alignment with the die-plate, to perforate the record in a place corresponding to the said position of the associated indicating device, and means for directly coupling each of said punch carriers to its associated indicating device comprising a gear transmission between each punch carrier and its associated indicating device, said gear transmission having a total width not substantially exceeding the width of the associated group of punches, whereby the punches as a whole can be disposed substantially in the same plane as the indicating devices.

4. In record-perforating punching mechanism

5 of the class to be used with a plurality of driven indicating devices, one of said indicating devices being provided for each denomination of the information to be recorded, a plurality of groups of punches, each group being associated with one of said indicating devices, and each punch of each group corresponding to one indication on the indicating device with which the group is associated, a die-plate co-operating with the said punches, means for feeding a record blank between said punches and said die-plate, means for providing relative movement between the said punches and said die-plate to perform the punching of all values of all denominations in one punching operation, a plurality of punch setting devices comprising co-axially arranged gear wheels and drum-like units, the punches being helically disposed around the peripheries of the said units, each of said punch setting devices being operatively associated with one group of punches and with the indicating device associated with the said group of punches, so that in any operative position of each indicating device the associated punch setting device is in a position relatively to said indicating device in which one punch of the associated group of punches is selected in alignment with the line of punches, to perforate the record in a place corresponding to the said position of the indicating device, and means for directly coupling each of said punch setting devices to its associated indicating device comprising a gear transmission between each punch setting device and its associated indicating devices, said gear transmission having a total width not substantially exceeding the width of the associated group of punches, whereby the punches as a whole can be disposed substantially in the same plane as the indicating devices.

DANIEL BRODO.

CERTIFICATE OF CORRECTION.

Patent No. 2,265,754.

December 9, 1941.

DANIEL BROIDO.

It is hereby certified that error appears in the above numbered patent requiring correction as follows: In the heading to the printed specification, line 6, strike out "In Great Britain November 18, 1937"; and that the said Letters Patent should be read with this correction therein that the same may conform to the record of the case in the Patent Office.

Signed and sealed this 1st day of December, A. D. 1942.
